UNITED STATES PATENT OFFICE.

GUY M. GEST, OF CINCINNATI, OHIO.

CONDUIT-SECTION FOR MANHOLE-TERMINALS.

SPECIFICATION forming part of Letters Patent No. 739,853, dated September 29, 1903.

Application filed July 12, 1902. Serial No. 115,311. (No model.)

To all whom it may concern:

Be it known that I, GUY M. GEST, a citizen of the United States, residing at Cincinnati, in the county of Hamilton and State of Ohio, have invented certain new and useful Improvements in Conduit-Sections for Manhole-Terminals, of which the following is a specification.

This invention relates to conduit-sections for manhole-terminals; and its object is to provide a conduit-section for electrical conductors of vitrified material and of such form and construction as to adapt it for ready connection with a manhole structure.

It is important in joining conduit-sections to manholes to provide flared or rounded surfaces at the juncture of the manhole with the conduit, so that the conductor-cables arranged within the conduit may be passed into the manhole without bending them too abruptly, and by providing a terminal connection of the required construction in a single integral section of vitrified material the work of joining a conduit to a manhole structure is materially lessened and the connection when made presents smooth rounded surfaces, over which the conductor-cables incased within the conduit may be bent without injury. It is also important that the outer surfaces of said sections, including the ends thereof, should be so formed as to contact closely when a plurality are laid side by side, as shown in Figures 3, 4, and 5, or in order to be readily built in with masonry, as shown in Figs. 2 and 5.

With the view of accomplishing this purpose my invention consists of a conduit-section for manhole-terminals of the novel construction hereinafter fully described in connection with the accompanying drawings and defined in the appended claims.

In the drawings, Fig. 1 is a view in perspective of a simple embodiment of the invention. Fig. 2 is a central horizontal section of the same. Fig. 3 is a perspective view of a modified construction and arrangement of the improvement. Fig. 4 is a similar view of a further modification, and Fig. 5 is a section on the line 5-5 of Fig. 4.

Corresponding parts in all the figures are denoted by the same reference characters.

Referring to Figs. 1 and 2, the numeral 1

designates the conduit-section, having a central bore 2 for the reception of electric conductors and an enlarged head 3, tapered on each of its four outer-surfaces 4. The smaller end 5 of the section is adapted to be connected by any suitable means to the other sections constituting the conduit, and the enlarged head 3 is designed to be embedded in the manhole-structure. The end of the head communicating directly with the manhole has its walls 6 flared outward to present rounded surfaces, over which the conductors may pass without forming sharp or abrupt bends therein.

In the modification shown in Fig. 3 the terminal section comprises two vertically-divided members 7 and 8, arranged one upon the other and having their meeting faces flattened to form a close joint. The remaining three sides 9 of each member are tapered, and the three inner walls 10 of the same are outwardly flared, so that when joined, as shown in the drawings, the section as a whole presents four flared or tapered sides similar to the integral structure shown in Fig. 1.

The modification illustrated in Figs. 4 and 5 embodies the same characteristic features as the forms shown in the other figures, the distinction being that in this modified construction the terminal section is made up of two members arranged side by side in parallel relation and having their inner meeting faces flat to effect a close joint. The other three faces of the members 12 and 13 are flared; and their inner walls 14 are correspondingly flared for the purpose named.

It is desirable that the inner curve of the surfaces of the flared portions of the terminals should commence at and extend from the surface of the manhole-wall inwardly in order to avoid an angular bisection of said wall by said inner curved surface. Therefore I prefer to form the inner curved surfaces, at least approximately, as a quadrant of a circle, the manhole-wall being tangential thereto, and in order to secure such a curve of suitable radial dimensions I construct my terminals with outwardly-flaring ends, as hereinbefore mentioned.

Flared terminal sections, substantially such as described and embodying my invention, may be manufactured in various shapes

and sizes to adapt them to meet varying requirements of conduit-building whether of simple or multiform construction.

As shown by dotted lines in Fig. 2, the outer face of the section may be flat, if desired, the essential feature being to have the inner faces of the terminal sections flared or beveled.

I would have it understood that the invention includes not only the constructions herein described, but also all such further modifications and variations in the details of form and arrangement as fall within the scope of the following claims.

Having thus described my invention, I claim and desire to secure by Letters Patent—

1. A conduit-section for manhole-terminals and comprising a body which is rectangular in cross-section, and has an outwardly-flaring end which extends transversely of and beyond the surface of the body, the inner surface of said end being curved longitudinally of the conduit-section.

2. A conduit-section for manhole-terminals, comprising a body which is rectangular in cross-section and has an outwardly-flaring

end portion extending transversely of the body, the inner face of said flaring end forming a surface curved longitudinally of the conduit-section.

3. A conduit-section for manhole-terminals and comprising a body which is rectangular in cross-section, and has an outwardly-flaring end which extends transversely of and beyond the surface of the body, the surfaces of said end being curved longitudinally of the conduit-section, the form of the inner surface of said end being a quadrant.

4. A conduit-section for manhole-terminals comprising a plurality of conduits each of which has a body which is rectangular in cross-section and having each an outwardly curved or flared flange upon the edges which form the outer edge of the group of conduit-sections.

In testimony whereof I have signed my name in the presence of the subscribing witnesses.

GUY M. GEST.
